DEVICE FOR PRODUCING AN AIR CURTAIN

David A. Whitbread, Luton, England, assignor to
F. Brauer Limited, Harpenden, England

Filed Sept. 17, 1974, Ser. No. 506,861

Term of patent 14 years

Int. Cl. D23—04

U.S. Cl. D23—151

FIG.1.

FIG.2.

FIG.3.

FIG.4.

FIG.5.

FIG.6.

FIG. 1 is a rear elevational view of a device for producing an air curtain showing my new design;

FIG. 2 is a top plan view thereof;

FIG. 3 is a front elevational view;

FIG. 4 is a bottom plan view thereof;

FIG. 5 is an enlarged end elevational view thereof;
and

FIG. 6 is a front perspective view thereof.

I claim:

The ornamental design for a device for producing an air curtain, as shown and described.
